Primary Examiner—Terry A. Wallace*Attorney, Agent, or Firm*—William D. Harris, Jr.; Harris, Tucker & Hardin[57] **CLAIM**

The ornamental design for a food dispenser gun, as shown and described.

DESCRIPTION

FIG. 1 is a front perspective view of a food dispenser gun showing my new design;

FIG. 2 is a front elevation view thereof;

FIG. 3 is a right side elevation view thereof, the opposite side being a mirror image;

FIG. 4 is a rear elevation view thereof;

FIG. 5 is a top plan view thereof;

FIG. 6 is a bottom plan view thereof;

FIG. 7 is a front elevation view of an alternate embodiment of FIG. 1;

FIG. 8 is a front elevation view of an alternate embodiment of FIG. 1;

FIG. 9 is a front elevation view of an alternate embodiment of FIG. 1;

FIG. 10 is a front elevation view of an alternate embodiment of FIG. 1;

FIG. 11 is a front elevation view of an alternate embodiment of FIG. 1;

FIG. 12 is a front elevation view of an alternate embodiment of FIG. 1; and,

FIG. 13 is a front elevation view of an alternate embodiment of FIG. 1.

The only difference between the embodiments is the nozzle portion shown in the front views. The remaining views being identical.
